UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL MACHINE.

1,197,034.

Specification of Letters Patent.

Patented Sept. 5, 1916.

Application filed September 28, 1915. Serial No. 53,038.

To all whom it may concern:

Be it known that I, GEORGE P. KINGSBURY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States to O. Mergenthaler, No. 436,582, wherein circulating 15 matrices are released from a magazine in the order in which their characters are to appear in print and then assembled in line, the composed line transferred to the face of a mold, the mold filled with molten metal 20 to form a slug or linotype against the matrices which produce the type characters thereon, and the matrices thereafter returned through a distributing mechanism to the magazine from which they started.

25 More particularly, it relates to machines equipped with a plurality of magazines containing matrices of different font or face, any selected one of which may be brought into action at will. In one class of such 30 machines, the magazines are arranged in fixed relation to an assembler entrance having throats or branches leading thereto, each magazine being provided with its own series of escapements to control the release 35 of the matrices therefrom, and the several series of escapements being actuated by reeds which extend through the throats or across the ends of the magazines beneath, thus requiring the matrices to pass between 40 the reeds as they are released from the lower magazines. This arrangement of the actuating reeds necessarily restricts the size or thickness of the matrices which can be used in the magazines, as the spaces between adjoining reeds is limited and cannot be increased without altering the entire keyboard mechanism or the magazine construction.

45 My present invention is intended to avoid the above objections and aims to provide a 50 construction wherein the matrices may be released from the several magazines without having to extend the escapement actuating reeds across any one of them, and thus to

allow the use of matrices of any size which the magazines themselves are capable of 55 handling. I secure this result, specifically, by operating the escapements of an upper magazine by or through the medium of the matrices in an underlying magazine, in a 60 manner which will be fully described in the detailed description to follow and finally 65 pointed out in the claims.

Referring to the drawings: Figure 1 is a vertical section through the magazines and assembling mechanism of a linotype machine, having my invention applied thereto; Fig. 2 is a similar view showing the parts in different position; and Fig. 3 is a section on the line 3-3 of Fig. 2.

70 The matrices X are stored according to font in the channeled magazines A, B, only two of which are shown herein, but of which a greater number might be employed if desired. These magazines are supported in the usual way upon the stationary base 75 frames A¹ and B¹ and in constant operative relation to the throats or branches C¹ of the fixed assembler entrance C, through which the matrices pass to the assembler as 80 they are released from the magazines.

85 The release of the matrices from the lower magazine B is controlled by a series of escapements suitably supported in the base frame B¹, and each comprising an angular pivoted lever D provided at its opposite ends with matrix-engaging pawls D¹ and D² which are projected alternately thereby into the corresponding magazine channel. The rear pawl D² is relatively short and is fixed to the rear arm of the lever D, while 90 the front pawl D¹ is considerably longer and is pivoted at its lower end to the forward arm of the lever so as to be slidable in guideways D^a of the supporting frame. Each of the levers D is also provided with 95 a depending arm D⁴ arranged in engagement with the hook-shaped end of the rod F suitably supported and guided in the machine frame by comb plates F⁶ and constantly urged downward by the spring F¹, 100 such downward movement of the rod being limited by the engagement of the shoulder F⁵ thereon with the upper one of the comb plates. The downward movement of the rod F by its spring F¹ serves to rock the 105 escapement lever D in one direction against

the action of the lighter spring D⁵, which tends to rock it in the opposite direction, so that to permit the spring D⁵ to act, the rod F must be raised against the action of its spring, and this is done in the usual way by the power-driven cam yoke F², which is controlled from the keyboard through the slide F⁴ and trip dog F³ in the well known manner.

- 10 In the normal position of the escapement, as shown in Fig. 1, the foremost pawl D¹ stands with its upper end in engagement with the forward end of the leading matrix in the magazine, being held in this position 15 by the downward pressure of the rod F. When, however, the rod is raised by the actuation of the keyboard mechanism, the spring D⁵ withdraws the pawls D¹ from the magazine to permit the escape of the leading 20 matrix and simultaneously projects the rear-most pawl D² into the magazine to arrest the following matrix, after which the escapement is restored to its former position by the return or downward movement of the 25 rod F, when the front pawl D¹ is again projected into the magazine and the rear pawl D² withdrawn therefrom, so that the following matrix which had been temporarily arrested by the latter will slide forwardly 30 and be engaged by and come under control of the pawl D¹.

The release of the matrices from the upper magazine A is controlled by a series of escapements suitably supported in the base 35 frame A¹ and each comprising a pivoted lever E provided at its opposite ends with matrix-engaging pawls E¹ and E², adapted to be projected thereby alternately into the corresponding magazine channel, and which 40 are formed respectively with shoulders E⁶ and E⁷ to limit the extent of their projection and of the rocking of the lever E in opposite directions. The pawls E¹ and E² are mounted to slide in guideways E^a of 45 their supporting frame, the latter pawl E² being pivoted at its lower end to the rocking lever E and the former pawl E¹ being pivoted thereto between its ends, as at E³, and having its lower end extending into an 50 opening B² in the upper side plate of the lower magazine B. The rocking of the levers E in one direction is effected by springs E⁵ bearing against the under sides of their rear arms, and their rocking in the 55 opposite direction is controlled by the lowermost matrices in the magazine B which are shifted edgewise for that purpose in the manner now to be described.

In the present instance, the escapements 60 of the lower magazine B are controlled in such manner that their forward pawls D¹ may be given an excessive upward movement or overthrow to lift the leading matrices edgewise into engagement with the down- 65 wardly projecting ends of the escapement

pawls E¹, the upper side plate of the magazine B being cut away on its inner face, as at B³, to permit such angular shifting of the matrices. Referring to Fig. 1, it will be noted that when the lower escapements are 70 in their normal position, as shown therein, the shoulders F⁵ of the rods F are held slightly above or out of contact with the upper comb plate F⁶, this being due to the engagement of a cam piece H¹ of a rock shaft or spindle H beneath the rear arms of the escapement levers D. When, however, the rock shaft is turned to disengage the cam piece H¹ from the levers D, the bars F are 75 immediately depressed by their springs F¹, and carry with them the arms D⁴ of the levers D, thus causing the latter to project the forward pawls D¹ up farther into the magazine, as illustrated in Fig. 2, the extent of such projection being limited by the 80 engagement of shoulders D⁸ on the pawls with the under side of the magazine. This further movement of the pawls D¹ causes the edgewise shifting of the matrices as 85 above intimated, it being noted that the 90 pawls are offset at their upper ends to provide angular recesses D⁶ wherein the lower ears on the under edges of the matrices fit, and which thus present lifting shoulders to engage the matrices as well as confining 95 shoulders to prevent their escape from the magazine when lifted. In this connection, it is pointed out that in their normal position the escapements for the upper magazine A stand in the position shown in the 100 several figures, with their front pawls E¹ in engagement with the leading matrices of the magazine, they being held in this position by means of a half-round rock shaft G, which prevents the action of the springs 105 E⁵ tending constantly to withdraw them from the magazine to permit the escape of the contained matrices.

The operation of the parts is as follows: When the matrices are to be released from 110 the lower magazine B, the parts should occupy the position shown in Fig. 1, that is, with the upper series of escapements held against action by the rock shaft G and with the cam piece H¹ in engagement with the 115 rear arms of the levers D of the lower escapements, which are thus caused to operate in their normal way to release the matrices from the lower magazine. If now it should be desired to deliver matrices from the upper magazine, the rock shaft H is first turned to the position shown in Fig. 2, allowing the lowermost matrices in the magazine B to be shifted edgewise into engagement with the pawls E¹ of the upper series 125 of escapements in the manner before described, and then the rock shaft G is turned to the position shown in Fig. 2 to bring its recessed or cut away portion above the rear arms of the levers E so that they may be 130

rocked by the springs E⁵. Such rocking, however, cannot take place immediately owing to the connection of the escapement levers E through the intermediate parts 5 with the rods F, whose springs F¹ are of sufficient strength to overcome the action of the springs E⁵. But when the rods F are raised by the operation of the keyboard mechanism, the springs E⁵ are allowed to 10 act, withdrawing the forward pawls E¹ from the upper magazine to permit the escape of the leading matrices therefrom and projecting the rear pawls E² into the magazine so as to arrest the following matrices temporarily. 15 As the pawls E¹ are thus withdrawn, they shift the engaged matrices in the lower magazine downwardly to their original or normal position therein, causing the escapement pawls D¹ of the other series of escapements to be depressed to a corresponding 20 extent. Then when the rods F are subsequently pulled down by their springs F¹, the escapement pawls D¹ are again shifted upwardly to their abnormal position, lifting 25 the matrices edgewise therewith and through their engagement with the forward pawls E¹ projecting the latter back into the upper magazine A and withdrawing the rear pawls E² therefrom, so that the previously arrested 30 matrices in the magazine may advance and become engaged with the forward pawls to be released thereby upon the next operation of the escapements. In changing from one 35 magazine to the other, therefore, it is merely necessary to move the rock shafts G and H either to locking or unlocking position, as the case may be. This movement of the shafts may be effected in any desired manner, either manually or by means of finger 40 key mechanism.

From the foregoing, it will be seen that the matrices from the upper magazine are released by or through the matrices of the lower magazine, thus avoiding the use of 45 reeds which extend across the latter for operating the escapements of the former, as has been the practice heretofore. Accordingly, there is no limitation imposed upon the size or thickness of the matrices which 50 can be used in the lower magazine.

In order to prevent the liability of the pawls D¹ being completely withdrawn from the lower magazine when its matrices are shifted downwardly by the escapement 55 pawls E¹, the rock shaft H is provided with a second cam piece H² which is so located thereon as to be moved above and across the rear arms of the escapement levers D when the cam piece H¹ is disengaged therefrom to 60 permit the delivery of matrices from the upper magazine, this relation of the parts being shown in Fig. 2.

As previously stated, I have shown my invention merely in preferred form and by 65 way of example, and it will be obvious that

many changes and modifications may be made therein without departure from its scope. Thus, the particular form of escapements may be different, or the shifting of the matrices effected by means other than 70 the escapements, or the selection of the magazines otherwise controlled. Many variations or alterations in these respects will readily suggest themselves to those skilled in the art.

Having thus described my invention, its construction and mode of operation, what I claim and desire to secure by Letters Patent of the United States, is as follows:

1. In a typographical machine, the combination of a plurality of magazines containing matrices, and means acting through 80 the matrices of one magazine to control the release of matrices from another.

2. In a typographical machine, the combination of a plurality of magazines containing matrices, and an escapement to control the release of the matrices from one magazine, the said escapement being operated by a matrix in another magazine. 85

3. In a typographical machine, the combination of a plurality of magazines containing matrices, an escapement to control the release of matrices from one magazine, the said escapement being operated by the 90 edgewise shifting of a matrix in another magazine, and means for effecting such edgewise shifting of the matrix.

4. In a typographical machine, the combination of a plurality of magazines containing matrices, and an escapement to control the release of matrices from each of the said magazines, the escapement of one magazine acting through a matrix therein to operate the escapement of another magazine. 100

5. In a typographical machine, the combination of a plurality of magazines containing matrices, an escapement to control the release of matrices from each of the magazines, and means for causing the escapement of one magazine to shift a matrix therein edgewise to operate the escapement of another magazine. 110

6. In a typographical machine, the combination of a plurality of magazines containing matrices, an escapement for each magazine, the escapement of one magazine having a variable throw so as to act when operated either to release a matrix from the corresponding magazine or to shift 115 said matrix edgewise to operate the escapement of another magazine, and means for controlling the throw of said escapement. 120

7. In a typographical machine, the combination of two magazines, an assembler entrance having throats or branches leading to the respective magazines, a series of escapements for each magazine to control the passage of the matrices therefrom to the corresponding entrance-throat, a single series 125 130

of actuating reeds connected to the escapements of the lower magazine, and means whereby said escapements for the lower magazine may be operated abnormally by 5 the reeds to shift the matrices therein edge-wise to operate the escapements of the upper magazine.

In testimony whereof, I have affixed my signature in presence of two witnesses.

GEORGE P. KINGSBURY.
